CLAIM

The ornamental design for a head bandage, as shown and described.

DESCRIPTION

FIG. 1 is a front perspective view of the present invention of a head bandage, shown in condition of use for clarity of disclosure;

FIG. 2 is a right side view thereof, the left side being a mirror image;

FIG. 3 is a rear view thereof;

FIG. 4 is a top view thereof; and,

FIG. 5 is a bottom perspective view thereof.

The equal-length broken line showing of a human head depicts environmental subject matter only and forms no part of the claimed design.

1 Claim, 5 Drawing Sheets
